UNITED STATES PATENT OFFICE.

FRED LACEY, OF LOWELL, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,362,111.

Specification of Letters Patent. Patented Dec. 14, 1920.

Application filed August 19, 1919. Serial No. 318,472.

To all whom it may concern:

Be it known that I, FRED LACEY, a citizen of the United States, residing at Lowell, in the county of Middlesex and State of Massachusetts, have invented an Improvement 5 in Feeler Mechanism for Looms, of which the following description, in connection with the accompanying drawings, is a specification, like characters on the drawings representing like parts.

This invention relates to feeler mechanisms for looms, whereby upon occurrence of substantial exhaustion of the filling in the shuttle, a fresh supply is automatically furnished.

In one type of feeler mechanism heretofore suggested, the feeler has had an engaging end portion which on detecting beats would engage the filling in the shuttle and be held from movement longitudinally of the shuttle until substantial exhaustion of the filling, but when the filling reached a condition of substantial exhaustion, the feeler was given a movement in a direction longitudinally of the shuttle to effect replenishment of filling.

The feeler mechanism of this invention relates to this general type, and has for its object to provide a feeler mechanism of the so-called "side swipe" type wherein the feeler may be lightly held in its rearward position by a yielding spring that will have no injurious effect upon the filling, and also wherein the feeler will impart to a feeler moving member, movements tending to move the feeler in a direction longitudinally of the shuttle when the filling is substantially exhausted.

The feeler moving member is preferably 40 formed, in the present instance, as a swinging member or lever having one end portion connected to the feeler by a spring which is placed under tension by frontward movement of the feeler, and is relaxed when the feeler member moves rearwardly.

The above and other features of the invention will best be understood from the following description in connection with the accompanying drawings which show one 50 good practical form of the invention.

In the drawing:—

Figure 1 is a perspective view of the detecting side of the loom, with the present invention applied thereto, and disclosing

sufficient of the parts to make clear the association of the invention therewith;

Fig. 2 is a plan view in detail showing the action of the feeler mechanism when, on a detecting beat the filling is substantially exhausted;

Fig. 3 is a section taken through the pivotal mounting for securing the feeler carrier to the feeler stand; and

Fig. 4 is a perspective view of a modified form of the feeler mechanism.

The loom frame 1 may be of suitable character for supporting the operating parts, and has connected thereto the brackets 2, one at each side of the loom frame for supporting the transverse or rock shaft 3, which is normally under the influence of a spring (not shown) tending to turn it counterclockwise (Fig. 1).

Secured to and extending from the transverse shaft 3 is the arm 4 to which is pivotally connected the block 5 having pivotally jointed thereto at 6 the actuator 7, the rear end portion 8 of which is adapted at times to be engaged by an operating member 9 which may be either the weft hammer 80 or cam follower, or a part connected or associated therewith, the construction being such that when filling replenishment is to be effected, the end 8 of the actuator 7 will be placed in the path of the operating member 85 9 to cause rocking movement of the transverse shaft 3 clockwise, and through such rocking movement to effect replenishment of filling through a well known train of mechanism.

The shipper stand 10 has adjustably connected thereto by the bolt 11 the feeler stand or support 12 which, in the present instance of the invention, is formed as a plate, to which is pivotally connected at 13 the feeler carrier 14, the construction being such that the feeler carrier may swing laterally or in a direction longitudinally of the shuttle. In the present instance of the invention, the feeler carrier 14 has the downwardly extending lug 15 into which may be tapped the screw 15^a for holding the feeler carrier and feeler stand in operative relation with capacity of the feeler carrier for pivotal movement.

The feeler carrier 14 has the rear bearing 16 and the front bearing 17 in which is mounted for reciprocation toward and from

- the front of the loom, the feeler 18 having the toothed engaging end portion 19. The rear and front bearings 16 and 17 may be formed by upwardly projecting lugs from the feeler carrier, as indicated, or otherwise contrived, the essentials in this respect being that the feeler 18 may have capacity for movement toward and from the front of the loom in the bearings.
- 10 Secured to the feeler 18 in front of the rear bearing 16 is a shoulder 20 between which and the rear surface of the front bearing 17 is interposed a spring 21 normally tending to move the feeler 18 rearwardly with permissive movement forwardly.
- 15 Associated with the feeler 18 is a feeler moving member which, in the present instance of the invention, consists of the swinging lever having positive connection with the feeler to be actuated thereby as the feeler moves forwardly and rearwardly. One good form of the feeler moving member consists of a lever 22 pivoted at 23 to a lug 24 extending laterally from the feeler stand.
- 20 25 Extending from the lever 22 is an arm 25 having a slot 26 which is engaged by a pin or roller 27 carried by the feeler 18, the construction being such that when the feeler moves forwardly or rearwardly, the positive connection between the arm 25 and feeler member, causes the latter to swing the feeler moving member or lever 22 upon its pivot.
- 30 35 Swiveled or pivoted to one end of the feeler moving member or lever 22 at 28 is a rod or pin 29 which extends laterally relative to the feeler and passes loosely through a lug 30 rising from the feeler carrier 14. Interposed between the swivel connection of the arm or rod 29 with the feeler moving member or lever 22 and the lug 30 is the spring 31 which is normally not under tension when the feeler is in its rearward position as indicated in Fig. 1. The spring 40 45 adjacent the lug 30 may be attached to a sliding collar 32 which, when the lever 22 is turned clockwise on its pivot, viewing Fig. 1, the collar 32 will bear against the projection or lug 30, and upon further movement of the lever 22 in the same direction, the spring 31 will be placed under compression as the rod 29 slides through the lug 30 and tend to move the feeler 18 in a direction longitudinally of the shuttle.
- 50 55 The feeler moving member or lever 22 has an end portion 33 which is adapted to bear against a stop or lug 34 projecting from the feeler carrier 14, the construction being such that when the feeler is moved rearwardly, and the lever 22 is swung upon its pivot 23 in a contra-clockwise direction, viewing Fig. 1, the end portion 33 will bear against the lug or projection 34 and tend to swing the feeler carrier and perforce the 60 65 feeler laterally or in a direction longi-

tudinally of the shuttle. A stop 35 may be provided on the feeler stand for limiting the lateral swinging movement of the feeler carrier as it is moved by the end 33 of the lever 22.

70

The feeler, through the feeler carrier, is connected to the actuator 7 by means of a link or rod 36, one end of which is connected to the feeler carrier at 37, and the other end of which is connected to the actuator at 38, the construction being such that upon lateral movement of the feeler or feeler carrier, the actuator 7 will be correspondingly moved to place its end 8 either in or out of the path of movement of the operating member 9.

75

The lay 39 may be of usual construction and provided with the shuttle-box 40, the front wall of which may be provided with an opening 41 to register with the corresponding opening 42 in the front wall of the shuttle 43 when the latter is in the detecting box, the parts being arranged so that upon a detecting beat the feeler 18 will pass through the slots 41 and 42 and 80 feel for the filling.

85

The feeler operating member or lever 22, as hereinbefore described, is pivoted to the feeler stand or an appropriate support adjacent the path of movement of the feeler member, and one end, in the present instance, the rear end of the moving member or lever 22 is yieldingly connected to the feeler through the feeler carrier at a point rearwardly of the pivotal connection between the feeler carrier and feeler stand, and the other end 33 of the moving member or lever 22 has a bearing against the feeler carrier forwardly of the pivotal connection 13 between the feeler carrier and feeler stand.

95

In Fig. 4 a somewhat modified form of the feeler moving member is shown. In this case the feeler moving member consists of a lever 44 pivoted to the feeler stand at 45 and connected to the feeler 18 by the pin and slot construction similar to that described for the preferred form. In the modified form illustrated by Fig. 4, the feeler moving member or lever 44 is normally under the influence of a spring 46, one end of which is connected with the rearwardly extending arm of the lever 44 at 47, and the other end of which is connected to a fixed point at 48, the tendency of the 100 spring being to turn the lever 44 clockwise in the illustrated form. Extending from the rear portion of the feeler moving member 44 is the pin 49 which is under the influence of a spring 50 tending to project 105 the pin 49 and cause it to normally bear upon a lug 51 extending from the feeler carrier 14 which, as hereinbefore described for the preferred construction is pivotally mounted at 13 on the feeler stand. The 110

115

120

125

130

front end portion of the feeler moving member 44 has bearing points 52 which, when the feeler is in its rearward position, rest against the portion of the feeler carrier frontward of its pivotal mounting 13, while the pin 49 rests against the feeler carrier at a point rearward of such pivotal mounting. A link 53 serves to connect the feeler carrier 14 with the actuator 7, the construction being such that on frontward movement of the feeler on a detecting beat, the feeler moving member 44 will be moved contra-clockwise and tend to turn the feeler carrier on its pivotal mounting in a clockwise direction. On rearward movement of the feeler 18 the feeler moving member will be moved in the opposite direction. In the modification shown by Fig. 4, it will be noted that the feeler is not provided with a spring acting directly upon it, but that it is moved toward its rearward position and held in such position by the spring 46 acting through the feeler moving member 44.

25 When a working supply of filling is present on a detecting beat, the toothed or roughened end 19 of the feeler will engage the filling, and the feeler will be moved frontwardly, thereby turning the feeler moving member and tending through the feeler moving member to effect movement of the feeler in a direction longitudinally of the shuttle. Under the conditions stated, however, movement of the feeler will be prevented by the filling. When, however, the filling is substantially exhausted and no longer able to hold the feeler from movement longitudinally of the shuttle, the feeler will be given such movement through the feeler moving member as the feeler moves frontwardly, and thereby effect replenishment of filling.

What is claimed is:—

1. In a feeler mechanism for looms, the combination of a feeler stand or support, a feeler carrier pivotally mounted on the stand or support to swing in a direction longitudinally of the shuttle, means for effecting replenishment of filling connected to the feeler carrier, a feeler mounted on the feeler carrier for movement toward and from the front of the loom, a feeler moving member pivotally mounted on the feeler stand or support and engaging the feeler carrier at two points, one in front of and the other in rear of the pivot of the feeler carrier, an arm extending from the feeler moving member between said two points, and a slotted connection between the arm and feeler and tending on reciprocation of the feeler to move it first in one and then in the opposite direction longitudinally of the shuttle.

2. In a feeler mechanism for looms, the combination of a feeler stand or support, a feeler carrier pivotally mounted on the stand or support to swing in a direction lon-

gitudinally of the shuttle, means for effecting replenishment of filling connected to the feeler carrier, a feeler mounted on the feeler carrier for movement toward and from the front of the loom, a spring normally acting to move the feeler rearwardly, a feeler moving member pivotally mounted on the feeler stand or support and engaging the feeler carrier at two points, one in front of and the other in rear of the pivot of the feeler carrier, an arm extending from the feeler moving member between said two points, and a slotted connection between the arm and feeler and tending on reciprocation of the feeler to move it first in one and then in the opposite direction longitudinally of the shuttle.

3. In a feeler mechanism for looms, the combination of a feeler mounted for movement toward and from the front of the loom and for swinging movement in a direction longitudinally of the shuttle, said feeler constructed and arranged to engage the filling on a detecting beat and to be held by the engagement therewith from such swinging movement until substantial exhaustion thereof, a pivotally mounted feeler moving member connected to the feeler for swinging movement thereby as the feeler is moved frontwardly and rearwardly, a yielding connection interposed between one end of the moving member and feeler and placed under compression by frontward movement of the feeler and tending when under compression to swing the feeler longitudinally of the shuttle, and means for effecting replenishment of filling when the feeler is thus moved on a detecting beat.

4. In a feeler mechanism for looms, the combination of a feeler mounted for movement toward and from the front of the loom and for swinging movement in a direction longitudinally of the shuttle, said feeler constructed and arranged to engage the filling on a detecting beat and to be held by the engagement therewith from such swinging movement until substantial exhaustion thereof, a pivotally mounted feeler moving member connected to the feeler for swinging movement thereby as the feeler is moved frontwardly and rearwardly, a yielding connection interposed between one end of the moving member and feeler and placed under stress by frontward movement of the feeler and tending when under stress to swing the feeler longitudinally of the shuttle, means for effecting replenishment of filling when the feeler is thus moved on a detecting beat, and an unyielding bearing between the other end portion of the feeler moving member and feeler acting to return the feeler laterally to feeling position as the feeler moves rearwardly.

5. In a feeler mechanism for looms, the combination of a feeler mounted for move-

- ment toward and from the front of the loom and for swinging movement in a direction longitudinally of the shuttle, said feeler constructed and arranged to engage the filling 5 on a detecting beat and to be held by the engagement therewith from such swinging movement by engagement with the filling until substantial exhaustion thereof, a pivotally mounted feeler moving member having a slotted arm connected to the feeler for swinging movement thereby as the feeler is moved forwardly and rearwardly, a yielding connection interposed between one end of the moving member and feeler and placed 10 under stress by forward movement of the feeler and tending when under stress to swing the feeler longitudinally of the shuttle, and means for effecting replenishment of filling when the feeler is thus moved on 15 a detecting beat.
6. In a feeler mechanism for looms, the combination of a feeler that is mounted for movement toward and from the front of the loom and in a direction longitudinally of 20 the shuttle and is held from such longitudinal movement by the filling on a detecting beat until substantial exhaustion thereof, means connected to the feeler to effect replenishment of filling when it is substantially exhausted, a feeler moving member provided with an arm having a positive connection with the feeler, a spring interposed 25 between the feeler and feeler moving member which is placed under stress by forward movement of the feeler and operates 30 to exert a force upon the feeler tending to move the feeler longitudinally of the shuttle and is relaxed by the rearward movement of the feeler.
- 35 7. In a feeler mechanism for looms, the combination of a feeler that is mounted for movement toward and from the front of the loom and in a direction longitudinally of the shuttle and is held from such longitudinal 40 movement by the filling on a detecting beat until substantial exhaustion thereof, means connected to the feeler to effect replenishment of filling when it is substantially exhausted, a pivotally mounted feeler moving member provided with an arm having a positive connection with the feeler, a spring interposed 45 between the feeler and feeler moving member which is energized by forward movement of the feeler and operated 50 to exert a force upon the feeler tending to move the feeler member longitudinally of the shuttle and is relaxed by the rearward movement of the feeler.
- 55 8. In a feeler mechanism for looms, the combination of a feeler stand, a feeler carrier mounted on the stand to swing in a direction longitudinally of the shuttle, a feeler slidably mounted on the feeler carrier for movement toward and from the front of 60 the loom, a feeler moving member having a

positive connection with the feeler and arranged to be moved by the movement of the feeler, yielding means interposed between said feeler and feeler moving member and arranged to be placed under stress by the 70 forward movement of the feeler to exert a force upon the feeler tending to move the same longitudinally of the shuttle, said feeler constructed to engage the filling upon a detecting beat and to be held by the filling 75 from moving longitudinally of the shuttle until substantial exhaustion of the filling, and means for effecting replenishment of filling when the feeler is moved longitudinally of the shuttle.

80 9. In a feeler mechanism for looms, the combination of a feeler mounted for movement toward and from the front of the loom and in a direction longitudinally of the shuttle and held from such longitudinal 85 movement on a detecting beat by engagement with the filling until substantial exhaustion thereof, means for effecting replenishment of filling when the feeler is moved longitudinally of the shuttle, and a 90 feeler moving member operatively connected to the feeler to be moved by a forward and rearward movement thereof, and means operated by said feeler moving member tending to yieldingly move the feeler 95 longitudinally of the shuttle to effect replenishment of filling as the feeler moves forwardly and to move it positively in the opposite direction as the feeler moves rearwardly.

100 10. In a feeler mechanism for looms, the combination of a feeler that is mounted for movement toward and from the front of the loom, a feeler moving lever connected to the feeler to be turned upon its fulcrum by 105 forward movement of the feeler, a spring between the feeler and the lever which is placed under stress tending to move the feeler longitudinally of the shuttle on a detecting beat, and connections between the 110 lever and feeler to restore the feeler to feeling position as the feeler moves rearwardly.

11. In a feeler mechanism for looms, the combination of a feeler that is mounted for movement toward and from the front of the loom and is supported to swing laterally, a lever pivotally supported independently of the feeler, connections between the feeler and lever for turning the latter on its fulcrum as the feeler is moved forwardly, a 115 yielding connection between the lever and feeler tending to move the feeler laterally as the lever is swung by the forward movement of the feeler, and parts between the lever and feeler which tend to move the 120 feeler laterally in the reverse direction as the feeler moves rearwardly.

12. In a feeler mechanism for looms, the combination of a feeler that is mounted for movement toward and from the front of the 125

loom and is supported to swing laterally, a lever pivotally supported independently of the feeler, connections between the feeler and lever for turning the latter on its fulcrum as the feeler is moved frontwardly, and connections including a spring between the lever and feeler tending to move the feeler laterally as the lever is turned in one direction, and to move the feeler laterally in the reverse direction as the lever is turned in the opposite direction.

13. In a feeler mechanism for looms, the combination of a feeler that is mounted for movement toward and from the front of the loom and also in a direction longitudinally of the shuttle and is held from movement

longitudinally of the shuttle on a detecting beat by engagement with the filling until substantial exhaustion thereof, a pivotally mounted feeler moving member connected to the feeler to be swung about its pivotal mounting by frontward movement of the feeler, a spring which, by frontward movement of the feeler is made to exert a force tending to give the feeler its movement longitudinally of the shuttle and which becomes effective for this purpose when the filling is substantially exhausted on a detecting beat.

In testimony whereof I have signed my name to this specification.

FRED LACEY.
